UNITED STATES PATENT OFFICE

AARON MENDELSON, OF BROOKLYN, NEW YORK.

CIGARETTE-BOX.

1,333,989.

Specification of Letters Patent. Patented Mar. 16, 1920.

Application filed June 14, 1919. Serial No. 304,335.

To all whom it may concern:

Be it known that I, AARON MENDELSON, a citizen of the United States, residing at New York city, borough of Brooklyn, in the county of Kings, State of New York, have invented certain new and useful Improvements in Cigarette-Boxes; and I do hereby declare the following to be a full, clear, and exact description of the invention, such as will enable others skilled in the art to which it appertains to make and use the same.

This invention relates to improvements in boxes or cases, and has special reference to improvements in cases for pocket use and more particularly for holding cigarettes or like commodities.

An object of the invention is to so mount the cigarettes that upon opening the case, said cigarettes will be caused to assume positions separate and radiating from each other or alternately one above the other so as to permit convenient removal of the cigarettes or like commodity singly and obviating the necessity of fumbling over them.

A further object of the invention is to improve and simplify the attaching means for the cigarette holders whereby to permit convenient attachment thereof to the hinge connection of the sections of the box or case; to provide a structure wherein the holders are moved automatically to oppositely inclined or crossed positions when the case is opened, means being provided for centralizing the sections of the case and to serve as a spring for opening the case upon the release of a catch which normally serves to hold the case closed, and also to provide for arranging the holders in spaced relation to permit the removal of the cigarettes or other articles held therein as hereinbefore specified.

A further and very important object of the invention is to provide an arrangement wherein a pivot or attaching member constitutes a mounting means upon which pivotal action of a support for one or more series of the holders, or the holders independently, are turnable, but which also serves as means for anchoring sections of a pintle or pivot forming the opening spring, as well as lugs constituting means for attaching the support for the holders to such pintle; thereby obviating the necessity of employing a large number of springs for

arranging the holders as specified or for 55 centralizing the support between the sections of the case when opened. In carrying out these objects a resilient section of wire having flat longitudinal faces, is made use of, said faces extending longitudinally and being preferably of regular arrangement, with the cross section thereof being octagonal, hexagonal, or other cross sectional shape of more or less number of faces whereby to provide means for fastening a member having 60 an opening with walls corresponding to several or all of those of the pivot, while permitting said members to rotate thereon with less friction than with a pivot of round 65 cross section.

With the above objects and others in view, the invention consists of certain combinations and arrangement of parts as will hereinafter appear as the specification proceeds, more fully described, illustrated and 70 claimed, it being a further object to provide a device which is simple in construction, durable and not likely to get out of working 75 order.

Reference is had to the accompanying 80 drawing forming a part of this specification, in which similar characters of reference indicate corresponding parts in all the views, and in which:

Figure 1 is a perspective view of a cigarette case employing one form of mounting means for the holders, and in which the pivot of the sections constitutes a spring 85 for holding the sections or lids of the case open after springing the same apart and for 90 centralizing the holders between the sections;

Fig. 2 is a longitudinal sectional view 95 thereof through one of the sections of the case;

Fig. 3 is an enlarged cross-sectional view 100 showing the manner of mounting the holders;

Fig. 4 is an end elevation of the device as shown in Fig. 2;

Fig. 5 is a perspective view of one of the 105 sections of the spring-forming pintle;

Fig. 6 is a perspective view of one of the lugs at the outer ends of the support which is adapted to turn on a pivot section;

Fig. 7 is a similar view of one of the lugs 110 to which an inner end of each pivot section is rigidly secured to connect the support thereto;

Fig. 8 is a view similar to Fig. 2, but showing a modified form of support for the holders;

Fig. 9 is an end elevation of the form of invention shown in Fig. 8;

Fig. 10 is a view similar to Fig. 8, partly in section, but showing a further modified form of support;

Fig. 11 is an end elevation partly in section of the device as shown in Fig. 10;

Fig. 12 is a fragmentary detail view showing the form of spring employed in the modification shown in Figs. 10 and 11 for centralizing the holders and opening the sections or lids of the case;

Fig. 13 is a detailed inverted perspective view showing the manner of mounting the individual holders on their supports;

Fig. 14 is an enlarged cross-sectional view through the sections of the case at the pivot and showing the manner of limiting the degree of opening of the sections or lids under the action of the spring pivot or otherwise;

Fig. 15 is a sectional elevation of a modified form of case and holder;

Fig. 16 is a vertical cross-sectional view of the form of device shown in Fig. 15 with one of the members of the holder shown in a dotted position sprung away from the other member;

Fig. 17 is an elevation of the dividing plate between the members of the holder, with a sectional view thereof;

Fig. 18 is a perspective view of a modified form of holder member;

Fig. 19 is a perspective view of a further modified form of case in which the holders are swung fan-like fashion between the sections thereof;

Fig. 20 is a fragmentary end elevation, partly in section, of the device shown in Fig. 19;

Fig. 21 is a sectional view through the pivot and showing the mounting of a holder which is centrally positioned between the sections;

Fig. 22 is a similar view, but showing a holder disposed at a different angle; and

Fig. 23 is a like view with the holder arranged at a different angle.

As illustrated in the drawings, the improved case for holding cigarettes, or other like articles or commodities, comprises a pair of sections or lids 1 and 2, which are in the form of metallic shells having by preference, rounded corners 3 and having co-acting pivot ears 4 through which the sections are hingedly or pivotally connected to swing relatively by means of a pintle or pivot 5 of peculiar construction as will be hereinafter more fully described. At the edges of the sections opposite to the interacting sleeves or ears 4, there is provided a spring catch 6 and a co-engaging projec-

tion 7, the spring catch being adapted to be depressed through the medium of a finger-piece 8 for releasing the catch and permitting the case to be opened. In order to limit the opening movements of the sections of the case to an extent less than a 180° angle, the ears of the sections adjacent to the hinge connections are provided with shoulders 9 produced by pinching the metal at said points whereby to engage the opposed section and take the jar incident to the opening of the sections as well as to facilitate the handling thereof and subsequent closing of the case.

Means in the form of a support or holder, 80 is provided between the sections, so that when the sections or lids are opened, said holder will be held equi-distantly or centralized between the sections with the cigarettes in convenient position for removal by 85 the fingers or directly by the mouth and without fingering them. To facilitate this, the pintle or pivot of the case comprises a pair of sections 10, the same being of a cross-section providing a series of flat faces, 90 the contour being preferably regular and the outer ends of each section being bent at right angles as shown at 11. The sections of the pivot are preferably made octagonal, hexagonal or the like, a polygonal cross-section between eight and twelve faces and of prismatic shape with an even number of faces, being preferably employed so as to provide for the proper mounting of the individual holders as will be presently described. The holders 12 and 13 are arranged in opposed series and carried by a support which is constituted by opposed connecting members 14 and 15 to which the opposed series of holders 12 and 13 are attached by 105 means of intermediate ears 14' and 15' in spaced alternating or staggered relation, so as to pivot in unison upon a central pivot 16. This pivot is of rectangular, hexagonal, 110 octagonal or other cross-section with flat faces and is engaged by a series of pivot ears 17 stamped out from the bottom portions of the holders 12 and 13 on either side of the ears 14' and 15' so as to freely turn on the pivot 16 and be held normally in 115 spaced relation through the medium of an expansible coil spring 18. This spring is mounted upon the pivot 16 about midway of its length and is provided with oppositely extending ends 19 engaging depressed portions 20 of the connecting members 14 and 15 so as to exert opposite tension against said connecting members and hold the opposed series of holders in spaced diverging relation when the case is opened as shown in 125 Fig. 1, but to permit said series of holders to move into alignment when the case is closed. In order to mount the entire support or holder within the case and to open the case by springing the sections thereof apart when 130

the latch is released, as well as to centralize the support, peculiar connection is made between the support and the sections of the pivot. As hereinbefore described, the sections of the pivot terminate at or near the center of the case and the interacting pivot ears 4 are made circular in cross-section so as to inter-fit and receive the sections, on which the ears may have free pivotal movement. By reason of making the sections of the pintle or pivot with flat faces, the ears bear on the edges and thus reduce the friction as compared to that which would be produced by a member of circular or round cross-section, while also facilitating the attachment of the support as will now be described. At spaced points on either side of the spring 18 are spaced lugs or standards 21, the same being provided at their upper ends with openings 22 of rectangular cross-section so as to be rigidly secured to the pivot 16 against turning and having at their lower ends openings 23 corresponding in cross-section to the cross-section of the pivot or sections forming the same, whereby to provide a rigid connection between the supports and the inner extremity of each section of the pivot. Near the outer ends of the supports and between the outermost ears of the sections and the adjacent ones inwardly thereof, lugs or standards 24 are positioned. These lugs are provided near their upper ends with openings 25 of rectangular cross-section and near their lower ends with openings 26 of circular cross-section, the openings 25 rigidly engaging the pivot 16 and the openings 26 permitting free turning of the sections of the pivot therein, near their outer angularly bent ends 11 which extend in opposite directions and engage the opposed sections of lids 1 and 2.

In this manner, the opposed series of holders besides being held separated by the spring 18 exerting tension against the opposite connecting members 14 and 15, to which latter the holders 12 and 13 are connected through the medium of the intermediate ears 14' and 15' as heretofore described, will be held centralized between the sections or lids of the case. This is due to the fact that the inner ends of the sections 10 of the pivot are anchored to the lugs 21 and freely turn in the openings 26 of the lugs 24, so as to exert equal tension in opposite directions against the opposed sections of the case through the medium of the angularly bent ends 11. The pivot sections are straight when the case is opened, but when the case is closed by moving the sections or lids thereof together, opposite tension is exerted against the extremities of the sections 10 at their outer ends through the medium of the engagement of the sections with the angularly bent portions 11, thereby twisting or torsioning the sections of the

pivot so that when the catch is released, said sections will exert opposite tension in the manner of a double-acting expansible spring, thereby opening the lids and centralizing the supports and holders therebetween. That is, the holders will be equidistantly pivoted between the lids or sections of the case and said sections will be limited in their opening movement through the medium of the shoulders 9 heretofore described. By this construction, the use of a large number of springs, and especially coil springs, is obviated, thereby greatly simplifying the construction of the box or case, as well as obviating unnecessary projecting parts and adding to the neatness and appearance of the device.

In Figs. 8 and 9 of the drawings a modification of the above described construction is shown, in which the individual holders 85 are attached to the connecting members in the same manner, said connecting members being preferably rectangular in cross-section as shown. However, in lieu of the rectangular or prismatic shaped pivot 16, a pivot 27 of circular cross-section is provided, upon which the holders are pivoted in the same manner, while a spring 18 is also employed to exert opposite tension against the connecting members 14 and 15 95 to separate the holders as hereinbefore described. However, in lieu of connecting the lugs or standard 21 and 24 to the pivot, a pair of lugs 28 are secured in spaced relation to one of the connecting members near the center portion thereof, and these lugs are provided with openings corresponding to the openings 23 in the lugs 21. Lugs 29 are secured to or formed integral with the same connecting member at the outer extremities thereof and are provided with circular openings corresponding to the openings 26 in the lugs 24, so as to receive the pivot sections in the same manner as described in connection with the other form 100 of the invention. In this form the lugs move intermediately between the connecting members 14 and 15 when the case is opened under the action of the opposed spring sections of the pivot, thereby disposing the support and holders equi-distantly between the opposed sections or lids of the case as and for the purposes hereinbefore described.

In Figs. 10, 11, 12 and 13 of the drawings, a further modification is shown, in which a single support 30 having upturned ends 31 is provided, there being a pivot 32 supported in said ends, the latter being in the form of apertured ears as shown. The opposed series of holders 12 and 13, in this instance, are pivoted through the medium of ears 33 to the pivot 32 and between successive opposed pairs of holders 12 and 13, oppositely acting expansible coil springs 34 130

are mounted on the pivot with their extremities 35 extending longitudinally in diametrically spaced relation and engaging the bottom portions of the opposed pairs of 5 holders to move the same into angular spaced relation, limited by abutment against the opposite edges of the cross-sectionally arcuate holder 30 as is more particularly shown in Fig. 11 of the drawings. By this 10 means, five of such springs are employed, the outermost holders being limited against outward displacement or translation on the pivot through the medium of the upturned ends or ears 31, and stops or spacers 36 engaged through the holder 30 and freely receiving the pivot 32 therethrough between spaced ears 37 produced by slotting the sleeves or ears 33 of the holders on either side of the innermost pair of holders, serve 15 to further prevent longitudinal shifting of the holders, thereby reducing as much as possible friction between the adjacent edges thereof during their pivotal movements. A plurality of apertured ears 38 are stamped 20 from and bent downwardly at right angles to the holder 30 so as to pivotally engage the pintle or pivot 39 which pivotally connects the sections or lids 1 and 2 of the case. These ears 38 are positioned between 25 the pivot sleeves or ears of the sections of the case and serve as attaching means for the holders through the medium of the support already described. In order to provide means for opening the box by separating 30 the sections or lids thereof in addition to limiting such separating movements, a pair of lugs 40 are attached to the holder equi-distantly on either side of the medial point of its length and in these lugs a pivot 35 41 is secured whereby to take a pair of tensioned coil springs 42 thereon. These springs have their outer ends anchored against the holder as shown at 43, and their inner ends are extended in opposite directions to provide spring arms 44 which engage the opposed sections of the case to 40 exert tension thereagainst and separate the sections when the catch is released to open the case. These springs also serve to hold 45 the support and the individual cigarette holders carried thereby, centralized between the opposed sections by exerting equal tension in opposite directions. This construction is particularly shown in Fig. 11 of the 50 drawings, while Fig. 14 shows the shoulders for limiting the opening movements of the sections or lids of the case.

In Figs. 15, 16 and 17 of the drawings, a further modified construction is shown, in 55 which the sections 45 and 46 of the case are made smaller and deeper, and are provided with the usual form of catch. These sections are provided near their side edges with spaced pivot ears 47, the intermediate 60 portions of both sections being without

pivot ears. A central support in the form of a division plate 48 is provided with a pivot ear 49 engaging between the innermost pivot ears 47 and the ear 49 is flattened or squared at its central portion as 65 shown at 50 so as to produce an anchoring means for the inner ends of the section of the pivot 51, corresponding to the sections 10 and having angular extremities corresponding to the extremities 11 bent to engage the opposed sections so as to be twisted in opposite directions when the case is closed and to open the same when the catch is released. By this means the holder is also held centralized or equi-distantly 70 spaced between the opposed sections of the case and the plate also serves for the pivotal attachment of opposed side members or retainers 52 at either side of the plate 48. The plate is provided with pivot ears 53 75 on either side of the central extension producing the ear 49 so as to receive a pivot 54, the latter having pivotally engaged thereon, spaced pairs of ears 55 of the opposed side members 52. These side members have flanged side and bottom portions and are corrugated so as to provide relatively spaced and independent compartments for the cigarettes on either side of the central holder plate 48, while the latter 80 serves as a divider between opposed rows of cigarettes which are supported therein spaced one above the other in alternate relation as is particularly indicated in Figs. 15 and 16 of the drawings by the alternate 85 solid and dotted lines at the top portions of the cigarettes. For this purpose, the plate 48 is stamped out near its bottom portion and the stamped out portions are bent alternately in opposite directions at right angles 90 thereto to provide supports or rests 56, there being three of such rests on one side of the plate and two of such rests on the other side of the plate, in a case having five compartments on either side of the plate for 95 holding ten cigarettes in all.

It is to be understood, however, that the sizes of the sections and parts, and thereby the capacity of the box may be varied at will so as to hold twenty or any other number of 100 cigarettes as will be found desirable and convenient. It has been explained, that the spring 51 through the medium of the sections thereof, serves to centralize the holder 105 between the opposed sections or lids of the case, and in order to retain the side members 52 against the cigarettes and holder plate 48, so as to retain the cigarettes from displacement, the ends of the pivot 54 are bent in 110 opposite directions at right angles as shown at 57 so as to engage the bottom portions of the opposed side members 52 and retain the same toward the plate. In this manner when the side members are displaced with 115 respect to the plate, the portions 57 are un- 120

der tension and will serve to return said side members to their original position as will be readily understood. In this form, the pivot is also composed of a pair of sections having a square or other polygonal cross-sectional shape, so as to eliminate the necessity of using coiled springs in the structure.

In Fig. 18 of the drawings, a modification of one of the side members of the holder is shown, in which in lieu of stamping out the dividing plate 48 of the holder so as to provide rests for the cigarettes in the manner described in connection with Figs. 15, 16 and 17 of the drawings, a side member 58 is employed, which member in this instance is provided with rounding corrugations to accommodate ten cigarettes on either side of the division plate of the holder. In this instance, the side member is stamped, molded or otherwise formed to produce bottom shoulders or rests 59 spaced from the bottom portions or rests 60 of adjacent rounding corrugations, and the portions of the side members beneath the rests 59 are made flat as shown at 61 and contiguous with the bottom portion 62 of said member. This bottom portion is provided with attaching ears 63 in the usual manner, for connecting it to the pivot 54 as heretofore described.

In Figs. 19 to 23 inclusive, a still further modified form of construction is shown in which the sections or lids of the case are connected by a single piece pivot 64 also of prismatic cross-section, and in the illustration shown as having an octagonal cross-section. This pivot is engaged by the pivot ears 65 of the opposed sections or lids and has its extremities 66 bent in opposite directions to engage the opposed sections whereby to hold the latter in open positions limited by the shoulders as heretofore described, when the catches release it. This pivot is normally straight, but is twisted or torsioned when the case is closed, due to the exertion of opposite pressure or tension against the ends 66, thus holding the pivot under tension when the case is closed. A plurality of holders 67 are mounted on the pivot 64 between the pairs of ears 65 and for this purpose the holders are provided with apertured lugs 68 having rectangular openings 69 so as to fit four of the faces of the octagonal cross-sectioned pivots and thereby fix the holders to the pivots against turning movement. The openings in the lugs 68 are disposed at different angles as shown in Figs. 21 to 23 inclusive, thereby causing the holders to assume or swing in a fan-like fashion between the sections of the case when the latter is opened, as is clearly shown in Fig. 19 of the drawings. The holders will all be in spaced relation, as well as the cigarettes or other articles carried therein and thereby their convenient removal will be permitted by the fingers or mouth as de-

sired. The holders are also disposed in diverged relation when the case is opened and the pivot is straight, rather than when the pivot is bent as in my prior Patent No. 1,160,988 of November 16th, 1915, in which the support for the holders is in the form of a separate support extending diagonally across the pivoted edges of the sections or lids. In either form, the holders are disposed in fan-like or sinuous condition when the case is opened, as heretofore described. In this form as well as the others, the pivot having a prismatic cross-section or a plurality of flat faces of regular contour, will reduce the friction between the parts pivotally connected and the ears will form separators between the respective holders whereby to prevent their frictional engagement such as would be likely to interfere with their free pivotal movement during the opening and closing of the case.

Having thus described my invention, what I claim and desire to secure by Letters Patent of the United States of America is:

1. A case of the class described comprising a pair of hinged lids having a pivot of polygonal cross-section connecting the same, a support carried by said pivot and held intermediately of the lids, means to limit the opening movements of the lids and means to hold said lids closed.

2. A case of the class described comprising a pair of hinged lids having a pivot of polygonal cross-section connecting the same, a support carried by said pivot, means to limit the opening movements of the lids and means to hold said lids closed, said lids having means to open the same when the last-mentioned means is released and to centralize the holder between the lids.

3. A case of the class described comprising a pair of hinged sections, a support between said sections, a pivot of polygonal cross-section for said sections, holders attached to said support, and spring means between the holder and sections to open the sections and centralize the support therebetween.

4. In a case of the class described, a pair of hinged sections having circularly apertured bearing portions, a pintle of polygonal cross-section connecting said sections and received by said bearing portions, said pintle constituting means for opening the sections.

5. The combination with a pair of sections having pivot ears with apertures of circular cross-section; of a pivot of polygonal cross-section connecting the same, said pivot having oppositely bent ends engaging opposed sections and a support mounted between the sections and centralized by said pivot.

6. The combination with a pair of sections having pivot ears with apertures of

- circular cross-section; of a pivot of polygonal cross-section connecting the same, said pivot having oppositely bent ends engaging opposed sections and a support mounted on 5 said pivot to move therewith, said pivot exerting opposite tension to hold said support equi-distantly between the opposed sections when the latter are opened, and holders carried by said support.
- 10 7. The combination with a pair of sections having pivot ears; of a pivot connecting the same, said pivot having oppositely bent ends engaging opposed sections and being of polygonal cross-section substantially 15 throughout its length and a support mounted on said pivot, said pivot exerting opposite tension to hold said support equi-distantly between the opposed sections when the latter are opened, said pivot serving to 20 spring said sections apart and holders arranged in spaced relation and diverging with respect to adjacent holders, said holders being carried upon said support.
8. A case of the class described comprising 25 a pair of hinged lids, a support connected to the pivot of the lids, individual holders carried by said support, means to dispose said holders in spaced divergent relation when the case is opened by the separation 30 of the lids, means to open the case and to centralize the support and means to cause the holders to move outwardly with respect to the support.
9. A case of the class described comprising 35 a pair of hinged lids, a support connected to the pivot of the lids, a pivot member of polygonal cross-section carried by said support, individual holders carried by said support, and means including the pivot to 40 open the case and to centralize the support within the lid.
10. A case of the class described comprising 45 a pair of hinged lids, a support, a pivot member of polygonal cross-section carried by the pivot of the lids, individual holders carried by said support, and means including the pivot to open the case and to centralize the support within the lid, and means for limiting the opening and closing movements 50 of the lids.
11. In a case of the class described, a pair 55 of hinged lids, a support carried by the pivot of the lids, individual holders carried by said support, means to dispose said holders in spaced relation when the case is opened and means to open the case and to centralize the support with the holders branching therefrom.
12. In a case of the class described, a pair 60 of hinged lids, a support carried by the pivot of the lids, individual holders carried by said support, means to dispose said holders in spaced relation when the case is opened, means to open the case and to centralize the support with the holders branch-

ing therefrom, and means to limit the opening movements of the lids to an angle of less than 180°.

13. A case of the class described comprising 70 a pair of hinged sections, a support connected to the pivot of the sections, individual holders carried by said support to dispose said holders in spaced relation when the case is opened, means to open the case and to centralize the support with the holders branching therefrom, said pivot being of polygonal cross-section and exerting opposite tension to open the sections of the case.

14. A case of the class described comprising 80 a pair of hinged lids, a pivot for said lids, a pivot member carried by said first mentioned pivot, a support carried by the second mentioned pivot member, individual holders carried by said support, and means 85 cooperatively engaged with the lids, support and second mentioned pivot member for springing the lids of the case apart under equal tension in opposite directions and to hold the support and holders carried 90 thereby equi-distantly between said lids.

15. The combination with hinged sections; of a pivot of polygonal cross-section connecting the same, said sections being provided with pivot sleeves with round 95 bearing apertures and said pivot having oppositely bent ends co-operating with said sections to open the same.

16. A case of the class described comprising 100 a pair of lids, pivot ears carried in spaced relation by said lids and having openings of circular cross section, said ears being interacting, a pivot of polygonal cross-section substantially throughout their lengths connecting said lids and engaging 105 opposite sections at its opposite ends to normally hold the latter open, and means to limit the opening movements of the lids.

17. A case of the class described comprising 110 a pair of lids, pivot ears carried in spaced relation by said lids and having openings of circular cross section, said ears being interacting, a pivot of polygonal cross section connecting said lids and engaging opposite sections at its opposite ends to normally hold the latter open, means to hold 115 said lids in closed position, said pivot causing the separation of the sections when the last named means is released, and a support arranged upon the pivot and connected to the latter, said pivot holding said support equi-distantly between opposed sections.

18. The combination with hinged sections having interacting ears; of a pivot of 125 polygonal cross section engaging the same and having angularly bent ends also engaging opposed sections to separate the latter, and individual holders carried upon said pivot and moved into spaced divergent relation when the sections are opened, said 130

pivot being tensioned when the sections are closed and means to hold said sections closed.

19. The combination with sections having interacting ears and a pivot connecting the same to swingingly connect the sections, said pivot being formed in two sections each having a polygonal cross section and with their outer ends engaging opposed sections; of a support member having also a polygonal cross section, lugs fixed to said support member adjacent to the extremities thereof and having circular openings movably fitting the pivot sections, a pair of lugs secured to said support member in spaced relation near the medial portions thereof and fixed to the inner ends of the pivot sections, a pair of carrying members pivoted to said support and a plurality of individual holders arranged in series upon said carriers to be held in centralized relation to the opposed sections when the case is opened, and means to space said holders apart.

20. The combination with sections having interacting ears and a pivot connecting the same to swingingly connect the sections, said pivot being formed in two sections each

having a polygonal cross section and with their outer ends engaging opposed sections; of a support member having also a polygonal cross section, lugs fixed to said support member adjacent to the extremities thereof and having circular openings movably fitting the pivot sections, a pair of lugs secured to said support member in spaced relation near the medial portions thereof and fixed to the inner ends of the pivot sections, a pair of carrying members pivoted to said support and a plurality of individual holders arranged in series upon said carriers to be held in centralized relation to the opposed sections when the case is opened, and means to space said holders apart.

In testimony whereof, I affix my signature, in the presence of two witnesses.

AARON MENDELSON.
